UNITED STATES PATENT OFFICE.

KENNETH J. TOBIN AND WILLIAM W. DARROW, OF CHICAGO, ILLINOIS, ASSIGNORS TO CAMEL COMPANY, OF CHICAGO, ILLINOIS, A CORPORATION OF ILLINOIS.

SIDE-DOOR CONSTRUCTION.

Application filed December 11, 1925. Serial No. 74,765.

The present invention relates to freight car construction.

More particularly the present invention relates to freight cars designed for receiving relatively bulky lading, such, for example, as automobiles. In order to provide for the entry and removal of such bulky lading a construction of freight car has been provided having on each side a main door and an auxiliary door, said doors cooperating with a movable jamb. Said movable jamb may be united to said auxiliary door to move as a unit therewith, or, if preferred, may be separable from said auxiliary door. Said movable jamb should be of sturdy construction, should have convenient means for locking same in fixed position, and should provide a convenient structure for the insertion of a wood filler or nailing strip for coopering purposes.

Freight cars having main and auxiliary doors to provide a relatively wide door opening when such a wide door opening is required have proven very satisfactory in service, but, in so far as applicants are informed, such freight cars as heretofore known and used have not provided sufficient space for the insertion and removal of the larger types of automobiles. Automobiles are entered diagonally, that is—in angular relationship with both the longitudinal and transverse axes of the car, but even when great care is used difficulty has been encountered heretofore in handling relatively large automobiles.

An object of the present invention is to provide a freight car of the type referred to which will permit the entry and removal of relatively large automobiles without sacrificing any of the strength heretofore provided and without departing from standard practice in the width of door opening.

A further object is to provide an improved jamb construction which, without sacrificing strength, will leave a larger space for the diagonal insertion and removal of an automobile or other bulky article.

A further object is to provide an improved freight car construction which presents improvements over prior construction relating to protection against thieving, simplicity in assembling and assurance against difficulties due to warping in service.

Further objects will appear as the description proceeds.

Referring to the drawings—

55

Figure 1 is a horizontal sectional view of a part of a freight car embodying the principles of the present invention;

Figure 2 is a view in elevation taken from a point inside the car, said view being taken at 60 the lower extremity of the movable jamb;

Figure 3 is a view similar to Figure 2, but showing a view taken at the upper portion of the movable jamb; and

Figure 4 is a view of the movable jamb with 65 certain adjacent parts, only sufficient of the adjacent parts being shown to illustrate the functions of various parts of said jamb.

The numeral 1 indicates the main side door of one side of a railway freight car. Said 70 main door 1 cooperates at its left-hand side edge, as the parts are viewed in Figure 1, with the auxiliary door 2, said auxiliary doors lying in substantially the same plane as said main door. Secured to the auxiliary door 2 75 adjacent to its right-hand edge, as the parts are viewed in Figure 1, is the jamb which is indicated as a whole by the numeral 3. As noted above, said jamb 3 may be permanently secured to the auxiliary door 2 or may be 80 separable therefrom, though in the preferred construction said jamb is rigidly secured to said auxiliary door 2.

It has heretofore been proposed to use 85 rolled or pressed U-shapes and other shapes in the construction of the jamb 3, but in so far as applicants are informed said shapes have presented a rigid edge portion inwardly of the car in the direction of the door opening controlled by the main door 1. The 90 present invention contemplates a construction using a structural steel shape, but presented in a different manner from what has been heretofore known. According to the present invention, the section modulus of 95 said structural steel shape does not have to be reduced in providing the extra space required for the diagonal entry and removal of a bulky article such as a relatively large automobile.

100 The jamb 3 includes the angle 4, which may be a commercial rolled shape. Said angle 4 has one of its flanges, indicated by the numeral 5, disposed transversely of the car and the

other of its flanges, indicated by the numeral 6, disposed longitudinally of the car in the direction toward the door opening controlled by the main door. Said flange 6 is bent inwardly of the car a small amount for door guiding purposes, as will appear hereinafter. Mounted within the re-entrant angle of said angle 4 is the wood filler post 7, which constitutes a nailing strip for cooperating purposes, as is well understood by those skilled in the art. The wood filler post, of course, does not contribute materially toward the strength of the jamb, and for that reason no car strength is sacrificed if part of said filler post is removed to permit the passage of a bulky article. According to the present invention, said filler post 7 is beveled off at one of its vertical edges, that is—the edge presented inwardly of the car and toward the door opening controlled by the main door 1. The beveled off surface of the wood filler 7 is indicated by the numeral 8 and may, if preferred, extend only through a sufficient part of the height of the wood filler 7 to clear the fenders and hub caps of an automobile when said automobile is presented in the diagonal manner referred to above.

The cooperating edges of the main door 1 and auxiliary door 2 may be provided with the cooperating Z-bars 9 and 10, respectively. The outer flange 11 of the Z-bar 10 is flared outwardly as shown in Figure 1, whereby the main door 1, regardless of any warping which may occur in service, will be piloted into proper relationship with the auxiliary door 2 and the door jamb 3 by reason of the flaring jaws 6 and 11. Bolts 12—12 may be provided for holding the auxiliary door 2, Z-bar 10, angle member 4 and filler post 7 in rigid relationship with one another. Preferably, said bolts 12—12 should have rounded heads, as indicated by the numeral 13, whereby it will be impossible for a thief to loosen said bolts.

The movable jamb 3 may be guided at both top and bottom in its movement longitudinally of the car. The guide mechanism constitutes no part of the present invention, and, inasmuch as structure suitable for the purpose is well known to those skilled in the art, no description of same is pertinent in the present specification. In order to securely latch the movable jamb 3 in its home position, latching mechanism may be provided at both the top and bottom of the car, though if for any reason it should be preferred to lock said jamb only at the top, or only at the bottom, such a change will not depart from the present invention.

In order to latch the movable jamb 3 at the top, said jamb is provided with the pivoted latch member 14 adapted to have cooperative relationship with the keeper member 15, which may be riveted to the superstructure of the car. In order to latch the movable

jamb 3 at its lower portion, a pivoted latch 16 may be provided for cooperation with the keeper member 17, which should be riveted to the structure of the car.

In certain freight cars having movable jambs as heretofore provided the keeper member at the bottom of said movable jamb has been bolted in place, said bolts being readily accessible from underneath the box portion of the car. It is a relatively simple matter for thieves to remove one of said bolts adjacent to the latch member at the lower end of the movable jamb, and, by inserting a relatively long and slender member through the hole left by said bolt, to operate the locking mechanism of the jamb and effect entry to the car. The present invention contemplates a riveted structure, rivets 18—18 being provided for securing the keeper member 17 in place and for effectually baffling thieves attempting to effect entrance in the manner above referred to. The upper keeper member 15 is also riveted to the structure of the car structure to prevent tampering from the top of the car.

According to the structure illustrated, an operating rod 19 is provided in cooperating relationship with both the latch member 14 at the upper end of the jamb and the latch member 16 at the lower end of the jamb. Said rod 19 is provided with eye portions for enclosing portions of said latch members 14 and 16, and the weight of said rod 19 serves to bias said latch member to latching relationship with the keeper members 15 and 17. When said rod 19 is lifted, said rod will cooperate both with the latch members 14 and 16 to move same out of latching relationship with the keeper members 15 and 17. It has been proposed heretofore to provide a unitary control for latching members at the top and bottom of a post, but prior constructions have involved at flat strap for the rod 19. It has been proposed heretofore to provide an offset handle portion such as the offset portion 20 in the operating member 19, but difficulty has been encountered in shipping such operating members (prior to the time that said operating members have been installed in the car) due to the fact that said operating members tend to lengthen; or, expressed in other language, the offset portion 20 has tended to straighten out, the net effect being to increase the length of the operating member 19, requiring certain adjustment on the part of the artisan installing said operating member. The present invention contemplates the provision of a round bar. Considering equal cross sections of metal, the stiffness of the round bar is greater than is the stiffness of a flat bar, and the tendency to lengthen out at the offset handle section 20 is reduced.

As will be noted from an inspection of Figures 1 and 4, the operating bar 19 is dis-

posed along the flange 5 of the angle member 4, being held in cooperative relationship with said flange 5 by means of the straps 21—21. Said straps have portions extending along 5 the sides of the auxiliary door 2 and bolted to said auxiliary door by means of bolts 22—22. Bolts 23 may be provided for holding the straps 21, the filler post 7 and the angle member 4 in rigid relationship with one another. 10 If preferred, rivets 24 may also be provided for holding the straps 21 in position on the angle member 4.

By reason of the fact that the operating rod 19 according to the present invention is 15 round in cross section, the matter of shaping the straps 21—21 to conform thereto is simplified. Moreover, due to the rounded construction of the straps 21 at the region where they house the bar 19, more room is 20 provided for operating the nuts on the bolts 23. It will be noted that the operating bar 19 has a metal bearing, so that no difficulties are encountered due to warping of the wood filler post.

25 The present invention presents the advantage that the filler post may be replaced without disassembling the angle member 4 from the parts to which it is attached. By merely removing the nuts from the bolts 23 and 13, 30 it is a simple matter to remove a filler post and insert a new one. Inasmuch as said filler posts are subjected to rough usage in service, the advantage of ready removal and replacement of said filler post is a decided advantage 35 from a practical standpoint.

Though a preferred embodiment of the present invention has been described in detail, many modifications will appear to those skilled in the art. It is intended to cover 40 all such modifications that fall within the scope of the appended claims.

What is claimed is—

1. In a freight car, a main door, an auxiliary door, a movable door jamb cooperatively 45 associated with said auxiliary door, top and bottom keeper members for said jamb, said door jamb comprising an angular member having a wall disposed transversely of the car and a second wall disposed longitudinally of said car and extending toward the door opening controlled by said main door, said latter mentioned wall being bent inwardly of said car to provide guide means for said main door, and a filler post in the 50 angle between said walls, said keeper members and said filler post being disposed in substantial alignment when said jamb is in home position.

2. In a freight car, a main door, an auxiliary door, a movable door jamb cooperatively 60 associated with said auxiliary door, said door jamb comprising an angular member having a wall disposed transversely of the car and a second wall disposed longitudinally of said 65 car and extending toward the door opening

controlled by said main door, said angular member having mounted in the angle formed by said walls a wood filler post, said second mentioned wall being bent inwardly of said car to provide guide means for said main 70 door.

3. Freight car construction comprising in combination, a main door, a door jamb comprising an angular member having one wall disposed transversely of the car and another 75 wall disposed longitudinally of said car and extending toward the opening controlled by said door, a structural shape rigidly mounted relative to said jamb, said latter mentioned wall and a flange of said structural shape being flared to produce piloting means for said door.

4. Freight car construction comprising, in combination, a main door, a door jamb comprising an angular member having one wall disposed transversely of the car and another 85 wall disposed longitudinally of said car and extending toward the opening controlled by said door, a structural shape rigidly mounted relative to said jamb, said latter mentioned 90 wall and a flange of said structural shape being flared to produce piloting means for said door, said angular member having a filler post disposed in the angle formed by said walls.

5. Freight car construction comprising, in combination, a movable door jamb, latching mechanism disposed at the upper and lower ends of said jamb for latching same in fixed position relative to the remainder of said car construction, said jamb comprising a structural steel member, a door having sliding movements relative to said jamb, said structural steel member having a reentrant angle presented inwardly of said car construction 100 and toward the opening controlled by said door, a unitary latch operating member mounted upon said structural steel member and braces for guiding said operating member, said reentrant angle being free of obstructions inwardly of the car transversely thereof and longitudinally of the car toward said door opening.

6. Freight car construction comprising, in combination, a movable door jamb, latching mechanism disposed at the upper and lower ends of said jamb for latching same in fixed position relative to the remainder of said car construction, said jamb comprising a structural steel member, a door having sliding relationship relative to said jamb, said structural steel member having a reentrant angle presented inwardly of said car construction 115 and toward the opening controlled by said door, a unitary latch operating member mounted upon said structural steel member, and braces for guiding said operating member, said operating member constituting a round bar, said reentrant angle being free of obstructions inwardly of the car transversely 120

130

thereof and longitudinally of the car toward said door opening.

7. In a freight car, a main door, an auxiliary door, a movable door jamb cooperatively associated with said auxiliary door, keeper means for said jamb, said door jamb comprising an angular member having a wall disposed transversely of the car and a second wall disposed longitudinally of said car and 10 extending toward the door opening controlled by said main door, said angular member having mounted in the angle formed by said walls a wood filler post, said filler post having a portion of its exposed corner cut 15 away to provide clearance, said filler post being disposed in vertical alignment with said keeper means when said jamb is in home position.

8. Freight car construction comprising, in combination, a door jamb comprising an angular member having one wall disposed transversely of the car and another wall disposed longitudinally of said car and extending toward the opening controlled by said door, a structural shape rigidly mounted relative to said jamb, said latter mentioned wall and a wall of said structural shape being flared to produce piloting means for said door, said angle member having a filler post 25 disposed in the angle formed by said walls, said filler post having a portion of its exposed corner cut away to provide clearance.

9. Freight car construction, comprising, in combination, a sliding door, a door jamb, said door jamb comprising an angular member having a wall disposed transversely of the car and a wall disposed in the direction of the door opening controlled by said door, and a filler post in the reentrant angle between said walls, said angular member being free of obstructions to said reentrant angle in a direction inwardly of the car transversely thereof and longitudinally of the car in the direction of said door opening.

45 10. Freight car construction, comprising, in combination, a main door, an auxiliary door, a door jamb mounted on said auxiliary door, and a filler post, said door jamb comprising an angular member having a wall arranged transversely of the car and a wall disposed in the direction of the door opening controlled by said door, said angular member presenting an entrance for the post, said entrance being free of obstructions inwardly of the car transversely thereof and

longitudinally of the car toward the forward side of the door upon which said door jamb is mounted.

11. Freight car construction, comprising, in combination, a sliding door, and a door jamb, said door jamb comprising an angular member having a wall disposed transversely of the car and a wall disposed in the direction of the door opening controlled by said door, said angular member being free of obstructions to the reentrant angle between said walls inwardly of the car transversely thereof and longitudinally of said car in the direction of the door opening controlled by said sliding door. 70

12. Freight car construction comprising, in combination, a main door, an auxiliary door, a door jamb mounted on said auxiliary door in a position to co-operate with said main door; said door jamb including an angular member having a wall arranged transversely of the car and a wall disposed in the direction of the door opening controlled by said door, said angular member presenting an angular entrance for a filler post, said angular member being free of obstructions beyond a vertical plane including the edge of said second wall presented toward said door opening, which plane is disposed diagonally of said door opening and inclined toward said first mentioned wall inwardly of said car from said edge. 75 80 85

13. Freight car construction comprising, in combination, a main door, an auxiliary door, a door jamb mounted on said auxiliary door in a position to cooperate with said main door, said door jamb including a metallic structure, having one portion including a wall disposed transversely of the car and a second portion extending from said wall in the direction of the door opening controlled by said main door, said wall and said second portion providing a corner for receiving a filler post, said portions having free vertical edges disposed in a vertical plane lying diagonally of said door opening and inclined toward the plane of said wall inwardly of said car, said vertical plane comprising the boundary of said metallic structure transversely of said car and in the direction of said door opening. 90 95 100 105

Signed at Chicago, Illinois, this 7th day of December, 1925.

KENNETH J. TOBIN.
